UNITED STATES PATENT OFFICE.

FRANK ROBERT WOELZ, OF NEW BRUNSWICK, NEW JERSEY.

DESIGN FOR A CUTTER.

50,005.

Specification for Design.

Patented Dec. 5, 1916.

Application filed January 18, 1916. Serial No. 72,858. Term of patent 7 years.

To all whom it may concern:

Be it known that I, FRANK R. WOELZ, a citizen of the United States, residing at New Brunswick, in the county of Middlesex and State of New Jersey, have invented a new, original, and ornamental Design for Cutters, of which the following is a specification, reference being had to the accompanying drawing, forming a part thereof.

The figure is a perspective view of a cutter, showing my new design.

I claim:

The ornamental design for a cutter, as shown.

FRANK ROBERT WOELZ.

Witnesses:

ETHEL KOBINSON,
ELLA WOELZ.
